United States Patent Office.

JOHN W. LARMORE, OF HARRISON, OHIO.

Letters Patent No. 69,105, dated September 24, 1867.

IMPROVEMENT IN WHIFFLE-TREE.

The Schedule referred to in these Letters Patent and making part of the same.

TO WHOM IT MAY CONCERN:

Be it known that I, JOHN W. LARMORE, of Harrison, Hamilton county, Ohio, have invented a new and useful Whiffle-Tree; and I hereby declare the following to be a full, clear, and exact description thereof, reference being had to the accompanying drawings, making part of this specification.

The object of this invention is a form for a whiffle-tree which combines strength with lightness and elasticity, and which may be adapted so as to apportion a greater or less duty upon one or other animal, where more than one is used.

The stretcher A may be either of wood or iron, but I prefer to make it of wrought iron. I form in its extremities eyes or orifices $a a'$. B is a rod, whose ends being bent forward and passed through the apertures a terminate in hooks $b b'$. C is a hook, loop, or ring, having an eye, c , by which it grasps the rod B at or above its middle. D is a set-screw, which, being tapped through one side of the eye c , serves to hold the hook C to the middle or any other position on the rod B, according to whether it be desired to equalize or to vary the draught on the respective ends of the tree. E are springs, which, pressing upward against the hooks $b b'$, prevent the accidental disengagement of the team. The rod B, being capable of yielding slightly, lessens the jar incident to sudden starting and stopping.

I claim herein as new; and of my invention—

The arrangement of perforated stretcher A $a a'$, hooked rod B $b b'$, adjustable loop or hook C c , and set-screw D, for the purpose set forth.

In testimony of which invention I hereunto set my hand.

JOHN W. LARMORE.
